UNITED STATES PATENT OFFICE

ALFRED G. F. KUROWSKI, OF BROOKLYN, NEW YORK, ASSIGNOR TO UNDERWOOD ELLIOTT FISHER COMPANY, OF NEW YORK, N. Y., A CORPORATION OF DELAWARE

COMBINED TYPEWRITING AND CARD-PERFORATING MACHINE

Application filed July 22, 1926. Serial No. 124,147.

This invention relates to combined typewriting and card-perforating machines, and particularly to means whereby, for joint operation of a typewriter and card-perforator, the operation of any typewriter-key to print is translated and transmitted to the perforator as one or more punch-selecting or operating impulses. An object of the invention is to accomplish this by devices that are wholly mechanical as distinguished from the heretofore used means which involve the use of electromagnets, circuits, contacts, etc. By means of the selected punches, holes are subsequently punched in a card, the location of the holes in the card being descriptive of the characters printed by operation of the typewriter-keys.

One advantage resulting from the provision and use of the aforesaid wholly mechanical devices is an assurance of positiveness in the operation of the punch-selecting or punch-operating elements by the typewriter-keys. With the heretofore used electrical devices, this assurance has been lacking on account of the lack of absolute certainty in the operation of said electrical devices. For example, there might be defective contacts or defective operation thereof. By the operation of the typewriter-keys these contacts were actuated to close electrical circuits for causing the energization of electromagnets which, in turn, actuated the punch-selecting elements of the perforator. The failure of a contact or any other part of the electrical devices to function would result in improper punching, if, as is very likely, such failure escaped the immediate notice of the operator.

The invention is particularly useful in a machine of the type shown in my co-pending application, Serial No. 48,723, filed August 7, 1925 (now Patent No. 1,683,979, dated September 11, 1928). Such a machine, including the well-known Underwood typewriter and Powers key-punch, both of which are modified by an illustrative application of the present invention, is herein described and shown. The regular Powers key-punch, which will hereinafter be called the card-perforator, is of the type shown in Patent No. 1,287,706, to W. W. Lasker, dated December

17, 1918. Although the machines shown in my aforesaid pending application and in the present application are in the nature of the work they perform, only one adaptation of a combined typewriter and card-perforator, it will be understood that the invention is not limited to such an adaptation, and may be applied to other combinations of typewriting and card-perforating mechanisms.

The punches of the perforator shown are arranged, as usual, in forty-five parallel columns, each column having twelve punches. When a card is in position to be punched, each punch in each column registers with a corresponding hole-space in the card.

Included in the usual punch-selecting means there is, for each column of punches, a corresponding column of settable pins. Each pin is in longitudinal alignment with its punch, and the lower end of the pin is normally separated from the upper end of the punch by a gap. To select a punch, and thereby make it effective to perforate a hole-space in the card, the settable pin for said punch is depressed and latched in its depressed position, so as to close the aforesaid gap.

The usual die-plate, which co-operates with the punches, is movable up and down with the card. During the upward movement, the selected punches, reacting against the pins that are set against them, perforate the card, the punches not selected being pushed idly upward by and with the card. The usual stripper-plate guides the lower portions of the punches and moves with the die-plate from which it is separated by a gap which receives the card. During the downward movement of the die and stripper plates, which immediately follows their upward movement, the card is stripped from the punches. Each punch has at its upper end a shoulder, and, while the card is being stripped from the punches, the shoulders of said punches react against a fixed plate, which also guides the upper portions of the punches.

To depress the pins, there is provided for each pin-position in a column the usual pin-

60

70

75

80

85

95

100

setting plunger. In the present case there are twelve such pin-setting plungers, and they are arranged in a column which coincides with the arrangement of a column of pins.

- 5 The column of pin-setting plungers is mounted in a movable carriage, by means of which the column of plungers may be moved to register with any column of pins. When they so register, the corresponding pins and plungers are in longitudinal alignment, and their adjacent ends are separated by a small clearance to assure free movement of the carriage.

In the regular card-perforator the plungers are actuated to set pins, by key-controlled means, which are part of the regular perforator, and which also actuate an escapement-mechanism, whereby the perforator-carriage, under the pull of a spring-motor, is automatically shifted, so that the column of 20 plungers will register with the succeeding column of pins.

The purpose of combining the perforator with the typewriter is that the operation of the typewriter-keys to print shall also set 25 the pins of the perforator, so that the holes corresponding to the characters typed may be punched in a record-card. These perforated record-cards are used in the well-known processes of mechanical accounting. In the 30 adaptation of the combined typewriter and card-perforator herein shown, the typing is done on the record-card, and produces a heading on said card which is descriptive of the holes to be punched in the card. To insure 35 that the positions of the typewriter and card-perforator carriages shall always be in correct relation to one another, the carriages are positively coupled together, as shown in my aforesaid co-pending application, Serial No. 40 48,723.

After the heading has been typed, the card is removed from the typewriter and presented against feed-rolls of the perforator. Upon depressing the usual key, a machine-cycle of 45 the perforator is effected, which causes the feed-rolls to draw the card into punching position, and also causes the card to be punched according to the pins that were set by the operation of the typewriter-keys. 50 After the perforating cycle, the perforator-pins that were set are automatically restored during the return of the carriages to their starting positions, and the machine is ready to type and punch another card.

55 Some alphabetical characters and other symbols must necessarily be represented by more than one hole in a card-column, because a card-column has only twelve hole-positions, which are exceeded in number by the total 60 number of characters printed. In carrying out that part of the invention, which is directed toward means whereby the operation of the typewriter-keys may actuate the pin-setting plungers, there are provided first of 65 all mechanical translating means, whereby

only the pin-setting plungers corresponding to any operated type-key are caused to be actuated. The typewriter-keys, as usual, are mounted on key-levers.

A selection of the pin-setting plungers to be actuated is best accomplished by means which include a number of what may be called selector-members, which have edges that extend transversely of and underlie some suitable part of the typewriter type-actions. In 75 the present case there are twelve such selector-members, one for each pin-setting plunger, and they underlie the typewriter key-levers. A material edge that overlies and extends transversely of the edges of the selector-members will engage and displace only certain ones of the selector-members, if a suitable portion of and below the edge of each selector-member that is not to be engaged by 80 said material edge is cut away. For example, the letter M is represented in the card by the eleventh and twelfth hole-positions, and, therefore, when typing the letter M, the eleventh and twelfth selector-members must be actuated. In this case each of the other selector-members has its edge cut away where the aforesaid material edge related to the M-key would otherwise engage it, the cut-away portion forming a slot that clears the 85 material edge as it moves to displace the active selector-members. Each key has its own aforesaid material edge, which is preferably embodied in an interponent between the key-lever of said key and the edges of the selector-members.

In this manner the operation of a key is translated into the displacement of one or more selector-members, each of which corresponds to a pin-setting plunger. The invention further provides means whereby said 90 displacement is positively transmitted to said plungers, which are thus operated to set the corresponding pins. It is a feature of the invention that no part of said transmitting means is carried by the perforator-carriage, and there is therefore no tendency to impede the free movement of said carriage. Operating contact with the plungers is therefore best made by means of bars, the lower edges 95 of which are adjacent those portions of the 100 plungers with which such operating contact is made. In order that the plungers may be operated irrespective of the position of the carriage, said lower edges of the bars are necessarily parallel to and co-extensive with the 105 paths described by the aforesaid portions of the 110 plungers as the perforator-carriage moves from column to column.

In the present embodiment of the invention 115 the perforator is located behind the typewriter with the body of the perforator higher than the typewriter. Operating extensions of the plunger-actuating bars toward the typewriter are effected by making each of 120 said bars an upper chord of a light frame, 125 130

the vertical sides of said frame extending along and running close to the outer vertical sides of the perforator-frame. Each of the two sides is guided near its upper end for the up-and-down movement of the frame that is necessary to actuate the plungers. This up-and-down movement of each frame is derived from the up-and-down movement of the corresponding selector-member under the typewriter.

To transmit the up-and-down movement of the selector-members to the plunger-actuating frames, there is provided for each frame and corresponding selector-member a connecting rock-shaft having at each end an arm, both arms extending in substantially the same direction. The ends of each arm are connected respectively to the plunger-actuating frame and the selector-member. The shafts are of evenly varying lengths, so that the shafts with their arms may be nested one within the other. In the nested arrangement the shafts lie in a horizontal plane that is preferably below the typewriter and the body of the card-perforator.

The selector-members are preferably in the form of flat light plates and are mounted in guides for an edgewise up-and-down movement. The upper edges of the plates coact with transverse edges of the aforementioned interponents that are actuated by operation of the type-actions, and said upper edges are of a length sufficient to encompass all of the edges of said interponents. The plane in which the aforementioned connecting rock-shafts lie coincides approximately with the lower edges of the selector-member plates, which are of sufficient vertical depth to allow the plates to be properly guided. The two sides of each plunger-actuating frame are joined by a chord below the body of the perforator. A midway portion of each chord is extended edgewise and downwardly in the form of a panel, so that the lower edge thereof may be connected to one of the aforesaid connecting rock-shafts. A pin-and-slot connection joins each panel near its lower edge to an arm of said connecting rock-shaft, the other arm of which is operatively joined to the corresponding selector-member plate by an abutting connection, the end of the last-mentioned arm simply abutting against the lower edge of the plate. The interponents between the type-actions and the selector-member edges are guided in a fixture mounted on a platform that supports the typewriter, the interponents projecting through a hole in said platform, so that the lower edges of said interponents are below the bottom of the platform, which is separated from a lower platform by an intervening space in which the selector-member plates are arranged side by side. The selector-member plates are supported and guided in a fixture mounted upon the lower platform

and project through an opening in said platform, so that the lower edges of said plates are below the bottom surface of said lower platform. Against this lower surface, the bearings for the connecting rock-shafts are fastened, the shafts also being below said surface. Both platforms extend from the perforator-supporting frame. A spring is applied to each interponent to hold it in normal position. Suitable springs are also applied to each punch-selecting frame to counter-balance its weight and also the weight of the parts reacting upon said frame. The punch-selecting frame springs also hold the frames and said parts in their normal positions.

A further object of the invention is to provide a simple key-controlled power-drive, so that the fingers of the operator may be substantially relieved not only of the work required to operate the type-actions to print, but also of the extra work involved in simultaneously actuating the pin-setting plungers by the means herein outlined. A feature of said power-drive is that it may be applied to the typewriter with a minimum number of changes in said typewriter. To this end, there is provided a bar extending transversely of and below the key-levers. This bar is given a continuously and rapidly reciprocating edgewise movement of sufficient extent to operate the key-levers in a full stroke. This reciprocating movement is best derived by means of the well-known eccentric and co-acting slotted arm device, the slotted arm being fastened to a rock-shaft to which the bar is attached by arms. An electric motor drives the eccentric to which it is geared for a suitable speed. Each key-lever has pivotally attached to it a swingable member, a portion of which may, by swinging the member, be interjected into the path of said reciprocating bar, with a consequent displacement and operation of the typewriter key-lever to print. For each typewriter key-lever there is provided an auxiliary key-lever whereby the displacement of the corresponding swingable member into the path of the reciprocating bar may be selectively effected. The keys of these auxiliary key-levers constitute an auxiliary keyboard, and said auxiliary key-levers are so disposed that the auxiliary keyboard is just above the regular typewriter-keyboard with sufficient space between the two keyboards to permit free operation of the auxiliary key-levers. The interjectable portions of the aforesaid swingable members can only be fully interjected into the path of the reciprocating bar when the bar is at the extremity of its upward movement. In order that an auxiliary key-lever may be operated in an interval between such extremities, a yieldable operating connection is provided between each auxiliary key-lever and the swingable member of the corresponding typewriter key-lever.

Other features and advantages will herein-after appear.

In the accompanying drawings,

5 Figure 1 is a cross-sectional side elevation of a combined typewriter and card-perforator, showing features of the invention.

Figure 2 is a fragmentary side elevation of a typewriter key-lever and related parts, showing the relative positions of such parts 10 when an auxiliary key-lever has been depressed.

15 Figure 3 is a fragmentary side elevation of a typewriter type-action, and shows the relation of said type-action to the power-driven means whereby and when said type-action is operated to print.

20 Figure 4 is a perspective view of the invention, showing the means whereby the operation of a typewriter-key will actuate the punch-selecting mechanism of the card-perforator.

25 Figure 5 is a front elevational view of the combined typewriter and card-perforator, showing the features of the invention as seen in this view.

30 Figure 6 is a diagrammatic plan view of a typewriter-keyboard, key-levers and transverse selecting members, showing how said members must be cut so that only the ones corresponding to any operated typewriter-key will be actuated.

35 Figure 7 is a perspective view, showing the power-driven means for actuating the type-actions.

40 As shown in Figure 1, a typewriter is combined with a card-perforator for joint operation in which a record-card 10, placed around a platen 11 of the typewriter, may have a heading printed near its upper edge by operating the usual typewriter-key-levers 12, which swing about a fulcrum-rod 15 to actuate bell-cranks 16. Said bell-cranks 16, in swinging about a fulcrum 17, operate type-bars 18 to print against said card through an 45 inked ribbon, not shown. Every time a type-bar 18 prints, the usual Underwood escapement-mechanism, generally indicated by the number 19, is actuated by said type-bar to cause a carriage 20, in which the platen 11 is mounted, to move a letter-feeding step. The letter-feeding steps are impelled by the usual Underwood carriage-spring-motor, not shown. The key-levers 12 have mounted thereon the usual numeral-keys 13 and alpha- 50 bet-keys 14. In the joint operation of a typewriter and card-perforator, every time a character is typed, certain elements in the perforator are set that subsequently cause perforations corresponding to the character 55 typed to be punched in the card.

60 The record-card is divided into columns, each having twelve hole-spaces. Since there are approximately forty-two keys in the typewriter, combinations of several hole-spaces in a column must be used to represent

some of the characters printed. The record-card has forty-five columns of such hole-spaces, and for each hole-space there is a corresponding punch 21 in the perforator, the punches being arranged in columns of twelve each. A side view of one of the columns of punches is shown in Figure 1. Coacting with said punches in the punching of a card, is a die-plate 22 having a hole for each punch. The die-plate is included in what constitutes a card-frame 23. Said card-frame also includes a stripper-plate 24, which is separated from the die-plate by a gap, which may receive the card to be punched. After the heading has been typed upon the card, it is removed from the typewriter by rotating the platen in the usual line-spacing direction until the card is free. When the card is free of the platen, it is slid rearwardly over table-surfaces 25 and 26, that are part of the typewriter-carriage, and into guides 27, one of which is shown in Figure 1. By means of these guides and a platform 28, on which said guides are mounted, the card is directed toward the first of several pairs of feed-rolls 29, against which the leading edge of the card is presented. The usual starting key, not shown, is then pressed to initiate an operating cycle of the card-perforator, and, during this cycle, the feed-rolls 29 draw the card into 90 punching position against a movable stop 30. The feeding of the card into punching position occurs during the first part of said cycle. During the last part of said cycle the frame 23, with the card in the aforesaid gap, is moved upwardly to effect punching of the card. In order that a punch may penetrate and perforate a card, the lower end of a pin 35 when interposed in the path of said punch, opposes said punch as it moves upwardly with the card. The pin 35 is interposed and latched in its depressed position. There is one of said pins for each punch and they are arranged in columns of twelve each. To latch the pins in their depressed position, there is provided, for each column of pins, a spring-pressed latch-plate 36. During the aforesaid cycle of the perforator, a main shaft 31 of the perforator makes one complete revolution, and from this revolution the upward 100 movement of the card-frame 23 is derived by means of a cam 32 fastened to said shaft and a rocker-frame 33, which constitutes the connecting means between said cam 32 and the card-frame 23. Punches for which no pins 105 are set are moved idly upwardly by and with the card. Immediately after the upward movement of the frame 23 with the card, the frame and card are retracted by the continued rotation of the cam during the remainder of 110 a cycle. During this retraction, the card is stripped from the punches, which have penetrated it, and, during this stripping action, the shoulders of the punches react against a fixed plate 37, which also guides the upper 115 120 125 130

ends of the punches. The lower ends of the punches are guided by the stripper-plate 24.

At the end of a perforating cycle, the punched card is still in the aforesaid gap of the card-frame. The card is expelled from said gap at the beginning of a new cycle and simultaneously with the feeding of another card into punching position. At the beginning of said cycle, the card-stop 30 is withdrawn for a time long enough to permit the passage of the punched card. The punched card is deposited in a receptacle 49.

Punchings from the card drop into a pocket 38 attached to the under side of a perforator-platform 51. To facilitate the removal of said punchings, the pocket is provided with a hinged flap 39.

Thus it will be seen that the selection of the punches which are to perforate the card is effected by depressing and latching the pins 35 corresponding to said punches. The pins 35 are depressed in one column at a time. To depress the pins, there is provided a column of punch-indexing plungers 40 arranged to coincide with a column of pins. In order that the pin-setting plungers 40 may be moved to register with any column of pins 35, they are mounted in a carriage, generally indicated by the number 41. Said carriage is supported and guided by means of rails 42 and rolls 43. When a character is typed upon a card, the punch-indexing carriage 41 must be in a position corresponding to the typing position on the card. In order that the positions of the typewriter-carriage 20 and the punch-indexing carriage 41 shall always be in proper relation to each other, said carriages are coupled by means of a rack 44 supported on brackets 45 on the perforator-carriage, and a rack 46 supported on brackets 47 on the typewriter-carriage. A pinion 48 constitutes the coupling means between said racks, and is mounted on a column 49 supported by the platform 28. By means of said racks and pinion the two carriages always move in unison.

To secure the proper relative positions of the type-writer and the card-perforator, so that they may be coupled by said racks and pinion, the typewriter is supported upon a platform 50, which in turn is supported by the platform 51 of a perforator-frame, generally indicated by the number 52. A lower platform 53 is provided to support some of the connecting devices between the typewriter and the perforator, said connecting devices forming a part of the invention to be explained. Said lower platform 53 is separated from the platform 50 by front and rear studs 54. Spacers 55 establish a proper level for the platform 50. The lower platform 53 extends rearwardly as far as the rear edge of the platform 51, from which it is separated at the rear by

a spacer 56. Suitable bolts 57 secure the platforms 50 and 53 in their established positions.

As already explained, some of the characters printed must be represented by combinations of more than one hole in a card-column. An established code of such combinations is described and shown in my aforesaid co-pending application, No. 48,723, and in said code no more than two holes are required to represent any character of the usual typewriter-keyboard. Said code is also indicated in Figure 6. In order that the operation of any key-lever 12 may be translated for a proper selection of the corresponding punch-indexing plunger or plungers 40 to be actuated, there is provided below the typewriter a number of selector-members 58, one for each indexing plunger. Each of these selector-members 58 has a horizontal edge 59 that extends transversely of the key-levers 12. Since each of these selector-members 58 corresponds to an indexing plunger 40, a displacement of a selector-member is equivalent to displacing a plunger, if said displacement is transmitted to said plunger. To selectively displace the selector-members 58 by the operation of any key-lever 12, an interponent 60 is provided between each key-lever and the selector-members. A lower edge 61 of said interponent extends transversely of and encompasses the upper edges of all of the selector-members. Each interponent 60, disposed as shown, when displaced by the operation of its related key-lever, will displace only the selector-members corresponding to said key-lever, if the aforesaid edges 59 of the other selector-members are cut away adjacent the edge 61 of said displaced interponent. Each selector-member, therefore, has a number of slots 65, which clear the edges of all the interponents, with the exception that where an interponent, through its key-lever, is intended to actuate a selector-member, there is no slot or cutting away of the upper edge 59 of the selector-member. As seen in Figure 1, the interponents are in the form of an inverted T, and are guided in a fixture 62 that is supported by the platform 50. A spring 63 is applied to each interponent, to hold it in its normal position in which a bent-over tab 64, at the upper end of the interponent, bears against the lower edge of the key-lever 12. One end of said spring 63 is attached to the interponent, and the other end is attached to a suitable projection 65 from the fixture 62. As shown in Figure 1, the lower edges 61 of the interponents are below the platform 50, which has an opening 69 that clears the interponents and their supporting fixture 62. The selector-members 58 are in the form of light flat plates supported and guided for an edgewise up-and-down movement by guide-

70

130

rolls 66 pivoted on rods 66^a in fixtures 67 and 68, secured to the lower platform 53, see Figure 5. An opening 69^a in said lower platform 53 clears the selector-members, the 5 lower edges 70 of which are below the platform 53. On the under side of said platform 53, part of the operating extensions from said selector-members to the punch-indexing plungers may be conveniently disposed, as will be explained.

In order that operating contact may be had with the punch-indexing plungers in any position of the punch-indexing carriage 41, there is provided for each plunger 40 a bar 15 72. The lower edge of said bar 72 is aligned to the upper end of its corresponding plunger 40, said upper end being in the form of a bent-over tab 73 of sufficient width to insure operating alignment at all times with 20 the bar 72. The lower edge of each bar is parallel to, and at least co-extensive with, the path described by the upper ends of the traveling plungers.

The plungers 40 perform the same function as the usual plungers of the regular perforator. In the present invention they are actuated by the bar 72, and each plunger has a retracting spring 74, which holds the plunger in its normal position, in which a 30 shoulder 75 reacts against a composite plunger-spacing plate 76 mounted on the carriage 41, and made of separable members, to facilitate the insertion of the plungers in assembling.

35 The lower ends of the plungers are guided by a slotted plate 71, and are preferably free to lag behind the movement of the punch-indexing carriage, so that there shall be no tendency, on account of a relatively slow retraction of the plunger, to impede the movement of the carriage. For this reason the guide-slots of the plate are extended sufficiently toward the left to permit said lagging of the plunger ends, and the plunger-springs 40 74 are inclined sufficiently to yieldably hold said plunger ends in normal position against the right ends of the guide-slots, as shown in Figure 5. Each of the bars 72 forms an upper chord of a frame, generally indicated 45 by the number 77. Each of said frames 77 constitutes a stationary train of operating connections between a plunger and a selector-member 58. For this purpose, the sides 79 of the frames are directed downwardly and 50 along the outer side frames 80 of the main body of the perforator. A suitable opening 81 is provided in the perforator-platform 51, to clear the sides 79 of said frames. Below the platform 51 the sides 79 of each frame 55 are joined by a chord 82. A midway portion of each chord 82 extends downwardly and forms a panel 83. A lower portion 84 of said panel 83, like the lower edge of the selector-member 58, is below the lower platform 53, so as to be conveniently adjacent

the connecting means between the frames 77 and the selector-members 58. Said connecting means are preferably a series of shafts 85, one for each frame and corresponding selector-member. The shafts are of varying lengths, the shorter one connecting the inner frame with the inner selector-member, as shown in Figure 4, and the longer shaft connecting the outer frame with the outer selector-member. By thus progressively vary-

ing the lengths of the shafts, they, with their connecting arms 89 and 92 to the frames and selector-members, may be nested one within the other, as indicated in Figure 4. For sup-

porting the shafts, there is secured to the under surface of the platform 53 a bracket 86. Bearing holes for the shafts are in a series of bent-over tabs 87 formed at either end of said bracket 86. The end of each arm 89 is in the form of a bent-over tab 90 that

abuts against the lower edge of the corresponding selector-member. Connection be-

tween the arm 92 at the other end of the shaft and its corresponding frame, is made by means of a pin-and-slot connection 93.

90 It will be seen from Figure 4 that an edge- wise vertical displacement of a selector-member 58, caused by operating a type-action, causes an edge-wise vertical displacement of the frame 77, and consequently of the bar

72, the displacement of the bar 72 being effective to actuate a corresponding punch-indexing plunger. The frames 77 are guided at each side at their upper portions by slotted

brackets 78, which are attached to the perforator side frames 80. The lower portions of the frames are guided by means of slotted plates 81^a fastened to the lower platform 53.

A spring 88 on each side of each frame 77 keeps the frame in its normal position, in

100 which stop-pins 91, driven into the sides 79 of each frame, engage the brackets 78. One end of each of said springs 88 is anchored to the corresponding bracket 78, and the other ends of said springs are attached to the ad-

105 jacent sides 79 of the frames. The springs 88 also counterbalance the weight of the frames 77 and the train of mechanism be-

tween each frame and the levers 12. All of

110 the parts, constituting a mechanical train be-

tween the levers 12 of the typewriter and the punch-indexing plungers 40 of the perforator, are to be made as light as possible, so

115 that resistance against their operating dis-

placement is reduced to a minimum, and for

120 this reason said parts should be limited in size and number as much as possible without

sacrificing the rigidity necessary for their positive operation, which constitutes a fea-

125 ture of this invention. For example, the se-

lector-members 58 and the lower panels 83 may have their interior portions cut out, as indicated by openings 94 and 94^a, respec-

tively (see Figure 4).

In the preferred form of the invention,

power-driven means to operate the type-actions are provided to relieve the fingers of the operator, not only of the work necessary to operate the type-actions to print, but also of the work involved in operating the punch-indexing plungers 40 by the means herein described. As a source from which operating impulses for said type-actions may be derived, there is provided a rapidly-reciprocating bar 95, which extends transversely of and under the key-levers 12. The reciprocating movement of said bar 95 is derived by means of an eccentric 96, which coacts with a slotted arm 97 fastened to a rock-shaft 98, to which the bar 95 is secured by means of arms 99. The eccentric 96 is formed upon the side of a gear 100, which meshes with a driving gear 101 fastened to a shaft 102 of a driving motor 103. To support the gear 100 for rotation, there is provided a bracket 93^a mounted upon the platform 50, which also supports the driving motor 103. Said gear is preferably made to rotate upon a suitable stud secured in said bracket 93^a. If said gear 100 is journaled in a bearing hole in said bracket, said bearing hole must be of sufficient length to furnish proper bearing for the journal, which, in that case, is part of said gear. The rock-shaft 98 has its bearings in side frames 109 of the typewriter.

As an operating connection between the reciprocating bar 95 and each key-lever 12, there is pivotally attached to each key-lever 35 a swingable member 104, see Figure 7. Said swingable member 104 has a lower hook-shaped portion 106, which, by swinging the member, may engage the bar 95. Said hook-shaped portion is normally disengaged 40 from said bar. To effect the selective engagement of the hook-shaped portion, there is provided for each key-lever 12 an auxiliary lever 107. Said auxiliary levers are pivoted on a common fulcrum-rod 108, which 45 is supported by and between the side frames 109 of the typewriter. A stop-rod 110 determines the normal positions of said levers, and a stop-rod 111 determines the extent to 50 which said levers may be rotated. Each of said auxiliary levers is yieldably held in said normal position by means of a spring 112 secured to a bar 113 that is supported by and between the typewriter side frames 109. Suitable bracing means, not shown, may be 55 provided to support the rods 110, 111 and the bar 113 against sagging. The spring-bar 113 may be similarly braced by means, not shown. The outer arms of the levers 107 are formed so that keys 105, mounted on the 60 ends of said outer arms, constitute an auxiliary keyboard above the regular typewriter-keyboard, said auxiliary keyboard being substantially a duplicate of said regular keyboard. The inner arms 115 of said levers 65 107 are substantially uniform.

Operating connection between the arm 115 of each auxiliary lever 107 and the corresponding swingable member 104 is preferably made by means of a yieldable device that includes a lever 117 pivotally mounted adjacent the swingable member 104 and on the same pivot-center. A bent-over tab 118 of the lever 117 engages the edge of the swingable member 104, and said tab and said edge are drawn together by a spring 119, 70 which normally has the effect of making substantially one lever of the swingable member 104 and the lever 117. The upper arm of each lever 117 has a suitably curved portion 120, which lies in the path of the end of the arm 115, of the auxiliary lever. When said auxiliary lever is rocked, the curved portion 120 is displaced by the end of the arm 115, and the hook-shaped portion 106 is consequently caused to be interjected into the 80 path of the reciprocating bar 95. It is for the reason that the hook-shaped portion can only be interjected when the bar 95 is at the extremity of its upward movement, that the aforesaid yieldable device, including the 85 lever 117 and spring 119, is provided, and said yieldable device becomes effective if the auxiliary lever is actuated in the interval between such extremities. If the upper edge of the bar moves below the normal level 90 of the ends of the swingable members 104, said lower ends or upper edge should be beveled, so that a member 104 may ride over said bar if its hook-shaped portion 106 is in the path of said bar at the beginning of its 100 upward movement. Figure 2 shows an auxiliary lever 107 operated, and the corresponding hook-shaped portion 106 engaging the bar 95 at the extremity of the upward movement of said bar. At the end of the 105 ensuing downward movement of said bar the relative positions of the involved parts are as shown in Figure 3.

A spring 116 is attached to each lever 117 and keeps said lever with its related swingable member 104 in normal position, in which the lever 117 stops against a pin 114, projecting from the side of the key-lever 12. It will be seen that the power-driven means herein described for operating the type-actions may be easily applied to the typewriter with a minimum of change. It will be understood, however, that the invention may be used with any other form of power-drive 110 for operating the type-actions of the typewriter. The power-drive herein described is preferred on account of its simple and novel features, which make it economical to manufacture, install and maintain. It will also be understood that a power-drive for the 115 type-actions may be dispensed with, in which case the type-actions would be operated to print and actuate the pin-setting plungers by means of the regular typewriter-keys 13 and 14.

A blank card is adjusted to the platen 11, the carriage shifted to the letter-space position for the first character to be typed, the motor 103 started to continuously vibrate the bail 95, and a key 105 is depressed to the Figure 2 position to swing the member 104 that is pendent from the associated lever 12 into engagement with the bail, to be drawn downwardly to depress said lever, to throw its type-bar to typing position. The depression of the lever 12 engages the tab 64 to depress the interponent 60, which, in turn, depresses one or more selector-members 58 not provided with clearance slots 65. The depressed selector or selectors 58 engage the end or ends 90 of crank-arms 89 to rock shafts 85, to vibrate crank-arms 92 having pivoted connections to the frames 77, to pull the cross-bars 72 thereof downwardly to depress punch-indexing plungers 40 which depress punch-setting pins 35 that become automatically locked in their depressed positions. The release of the key 105 effects a letter-space movement of carriage 20 and a pin-space movement of the carriage 41 and the several parts of the mechanical train of connections actuated by the key 105 are restored by springs 88.

After typing the last character on the card, a series of punch-setting pins 35 remain locked and in punch-intercepting positions, so that when the typed card is removed from the platen, the card is fed to the rolls 29 and into the card-punching position under the punches 21, the depression of a trip-key, shown and described in my aforesaid pending application, operates to cycle the shaft 31 and the cam 32 to raise the card against the punches 21, and those punches that are intercepted by the indexed pins 35 are forced through the card to leave perforations, when the card is withdrawn, that are descriptive of the items previously typed on the card. The depression of the well-known carriage-return key, not shown, restores the typewriter-carriage, restores the pin-indexing carriage, and automatically releases the indexed pins 35 in a well-known manner.

It will be understood that the punch-indexing mechanism with its counterbalanced trains of connections to the levers 12 may be operated by the manual manipulation of the usual character-keys 13, and that when the power-driven mechanism is employed, the keys 105 become the operating keys, and the levers 12 become type-bar driving levers and not key-levers.

No claim is herein made for any feature of invention disclosed in the application of L. E. Lentz Serial No. 178,350. The claims in this case are limited to features not disclosed in said Lentz application.

Variations may be resorted to within the scope of the invention, and portions of the improvements may be used without others.

Having thus described my invention, I claim:

1. In a machine having typing keys and a card-perforating mechanism having rows of stationary punches, the combination with a row of punch-indexing elements, said elements being actuatable by the keys to index certain of the punches, means effective subsequently to perforate a card, by all of the indexed punches simultaneously, said punch-indexing elements being mounted in a traveling carriage to register with any row of punches, of a mechanical train of mechanism between said punch-indexing elements and typing keys, including a plurality of parallel bars mounted over, and effective to actuate said elements, whereby the typing of a character indexes certain of said elements to a row of stationary punches, depending on the character typed, said train of mechanism being effective at any letter-space position along the typing line of the card.

2. In a machine having typing keys and a card-perforating mechanism having rows of stationary punches to cover the card, the combination with a single row of punch-indexing elements mounted in a traveling carriage to register said indexing elements with any row of punches, of a plurality of punch-indexing bars, one bar for each punch-indexing element, said bars being coextensive with the travel of the punch-indexing elements, each of said bars being movable to actuate its punch-indexing element, and a mechanical train of mechanism between each bar and said typing keys, whereby the operation of any key to type vibrates certain of said bars, to selectively index punches representative of the character typed.

3. In a machine having typing keys and a card-perforating mechanism having rows of stationary punches coextensive with the face of the card, the combination with a single row of punch-indexing elements, mounted in a traveling carriage to register said indexing elements with any row of punches, of a plurality of bars, one bar for each punch-indexing element, said bars being coextensive with the travel of the punch-indexing elements, each of said bars being movable to actuate its related punch-indexing element, means including a plurality of selector-members, one connected to each bar and operable by said typing keys, each key being operable to selectively displace certain selector-members, depending upon the character typed, and mechanical connections between each bar and each selector-member.

4. In a card-perforating machine, the combination with a plurality of stationary perforating elements including punches for perforating a card and keys for typing upon the card, of a plurality of key-depressible punch-indexing traveling members, each member, when depressed by single operations

of the keys, setting up combinations of punches to subsequently punch holes in said card representative of the character typed, a mechanical train of connections, stationary with respect to the travel of the punch-indexing members, between each indexing member and each typing key, including a vertically-movable bar mounted over each punch-indexing member, whereby the typing of a character indexes certain perforator-elements, singly and in groups, according to a prearranged plan, depending upon the character typed by the movement of said bar, and means effective to co-operate with the indexed punches to perforate the card in one operation.

5. The combination with a typewriting machine, including character-typing keys, a stationary card-perforating device including punches and a traveling punch-indexing mechanism, of a mechanical train of key-controlled linkages stationary with respect to the travel of the punch-indexing mechanism and including a series of punch-selectors to actuate said indexing mechanism and a plurality of key-actuated interponents effective to move certain predetermined groups of said selectors at each operation of a key to progressively set up the stationary card punches during the travel of said indexing mechanism.

6. The combination with a typewriting mechanism, including character-typing keys, a stationary card-perforating mechanism including punches and a traveling punch-indexing mechanism, of a mechanical train of key-controlled linkages including a series of selectors to set up said indexing mechanism and a plurality of reciprocatable members, one for each key, said linkages with their reciprocatable members being stationary with respect to the travel of the punch-indexing mechanism, each selector having a plurality of notches on one edge to form a free path for those members which are not to actuate the selector, said selector effective to be operated by the balance of the members for which notches have not been formed, whereby a single movement of the key will produce a predetermined group of perforations in the card for each character typed, and card-carrying means operative to subsequently cause all the indexed stationary punches to perforate the typed card simultaneously.

7. The combination with a typewriting mechanism, including character-typing keys, a stationary card-perforating mechanism including punches and a traveling punch-indexing mechanism, of a mechanical train of mechanism operable by the keys, and stationary with respect to the travel of the punch-indexing mechanism and including a permutating device between the keys and the indexing mechanism, and connected to actuate the latter to progressively set up certain of the

stationary card punches during the typing of each character on the card, according to a predetermined system of punch-grouping to represent each character typed.

8. The combination with a typewriting mechanism, including character-typing keys, a stationary card-perforating mechanism including punches and a traveling punch-indexing mechanism, of a mechanical train of non-traveling mechanism permutatably movable by the keys and movable to actuate the traveling punch-indexing mechanism during the typing of a line on a card, and means to subsequently perforate the card by all of the indexed punches.

9. The combination with a typewriting mechanism, including character-typing keys, a stationary card-perforating mechanism including punches and a series of traveling punch-indexing mechanisms, of a series of movement-transmitting trains, one train for each punch-indexing mechanism, and mechanical permutating means selectively actuatable by the individual keys, to actuate said trains and thereby progressively set up the stationary card-punches in groups during the typing upon the card, and card-carrying means operative to subsequently cause all the indexed stationary punches to perforate the card and then withdraw the perforated card from the punches.

10. In a card-perforating machine having keys, the combination with a plurality of settable punches, and a plurality of punch-setting means arranged to travel into progressive co-operation with each settable punch, of a non-traveling bar for each punch-setting means universally operative at all positions traveled by said setting means to set a punch, and means operatively connecting each bar to said keys to depress its punch-setting means.

11. In a card-perforating machine having keys, the combination with a plurality of settable punches, and a plurality of punch-setting means arranged to travel into progressive co-operation with each settable punch, of a non-traveling bar for each punch-setting means universally operative at all positions traveled by said setting means to set a punch, a selector-mechanism co-operative with each bar, and means, including a permutating mechanism, co-operative with said keys and with said selector-mechanisms to selectively operate certain groups of bars to simultaneously set a plurality of card punches by the depression of one key.

12. In a card-perforating machine having keys, the combination with a plurality of settable punches, a carriage, guides therefor, and a plurality of punch-setting means, on said carriage, arranged to travel on said guides into progressive co-operation with each settable punch, of a non-traveling bar mounted parallel with said guides for each

punch-setting means universally operative at all positions traveled by said setting means to set a punch, and means operatively connected to said keys to selectively vibrate said bars to depress punch-setting means corresponding to the character of the key depressed.

13. In a machine having keys and a card-perforating mechanism combined for a joint operation, the combination of a mechanical train of mechanism operable by said keys to set up said card-perforating mechanism, and means operably connected to said train of mechanism effective to normally hold said train in equipoise to soften the touch of the keys in setting up said card-perforating mechanism.

14. In a machine having keys and a card-perforating mechanism combined for a joint operation, the combination of mechanical trains of mechanism operable by said keys to set up said card-perforating mechanism and counterbalancing springs for each train of mechanism operative to normally hold said train in equipoise to reduce its operating resistance when operated by the keys.

15. In a card-perforating machine including keys, the combination with rows of settable pins, punches co-operating with said settable pins to perforate a card, a carriage traveling over said settable pins, and a row of pin-setting plungers mounted on said carriage, of a non-traveling bar for each pin-setting plunger operative at all positions of the traveling carriage to depress the same pin to set up a different punch-controlling pin, and means operatively connected to said keys to selectively depress said bars.

16. In a card-perforating machine including keys, the combination with rows of settable pins, punches co-operating with said settable pins to perforate a card, a carriage traveling over said settable pins, and a row of pin-setting plungers mounted on said carriage, of a non-traveling bar for each pin-setting plunger operative at all positions of the traveling carriage to depress the same pin to set up a different punch-controlling pin, and a mechanical train of mechanism connecting each bar and selectively operated by the keys.

17. In a combined typewriting and card-punching machine having typing keys, the combination with a plurality of normally inoperative punches arranged in longitudinal and transverse rows to cover the face of the card to be punched, and a single row of punch-indexing pins arranged to travel over the punches to register with each transverse row and index a punch therein, each character key operable to type and feed the row of punch-indexing pins step by step over each transverse row of punches, of a stationary pin-setting bar for each indexing pin op-

erable at any punch-indexing position longitudinally of the card, and a train of mechanism positively connected to each bar and operated by the keys in typing.

18. In a combined typewriting and card-punching machine having typing keys, the combination with a plurality of normally inoperative punches arranged in longitudinal and transverse rows to cover the face of the card to be punched, and a single row of punch-indexing pins arranged to travel over the punches to register with each transverse row and index a punch therein, each character key operable to type and feed the row of punch-indexing pins step by step over each transverse row of punches, of a non-traveling train of mechanism between the keys and each traveling punch-indexing pin operative to selectively and progressively set up a pin as each character is typed, and means to subsequently perforate the card with holes predetermined by the setting of the pins.

19. In a card-perforating machine having typing keys, the combination with a card-carrying platen movable letter-space distances as typing upon the card progresses, a series of stationary punches coextensive with the surface of the card to be punched and divided into vertical rows corresponding to the letter-spacing on the card, and a traveling carrier feedable letter-space distances in unison with the card-carrier and having a single row of punch-setting pins to engage each row of punches seriatim, of mechanical trains of mechanism normally stationary relatively to the travel of the punch-setting pin-carrier and operatively connected to be operated by the keys to depress punch-setting pins at any letter-space position of the pin-carrier as the typing upon the card progresses.

20. In a card-perforating machine having typing keys, the combination with a card-carrying platen movable letter-space distances as typing upon the card progresses, a series of stationary punches coextensive with the surface of the card to be punched and divided into vertical rows corresponding to the letter-spacing on the card, and a traveling carrier feedable letter-space distances in unison with the card-carrier and having a single row of punch-setting pins to engage each row of punches seriatim, of mechanical trains of mechanism normally stationary relatively to the travel of the punch-setting pin-carrier and operatively connected to be operated by the keys to depress punch-setting pins at any letter-space position of the pin-carrier as the typing upon the card progresses, each train of mechanism including an interponent for each key and selector-members operated by the interponent and connected to operate the punch-setting pins.

21. In a card-perforating machine having

typing keys, the combination with a card-carrying platen movable letter-space distances as typing upon the card progresses, a series of stationary punches coextensive with the surface of the card to be punched and divided into vertical rows corresponding to the letter-spacing on the card, and a traveling carrier feedable letter-space distances in unison with the card-carrier and having a single row of punch-setting pins to engage each row of punches seriatim, of mechanical trains of mechanism normally stationary relatively to the travel of the punch-setting pin-carrier and operatively connected to be operated by the keys to depress punch-setting pins at any letter-space position of the pin-carrier as the typing upon the card progresses, each train of mechanism including an interponent for each key, selector-members to be selectively vibrated by the interponent, and rock-shafts to be rotated by each selector-member and operatively connected to vibrate the punch-setting pins.

22. In a card-perforating machine having typing keys, the combination with a card-carrying platen movable letter-space distances as typing upon the card progresses, and a series of relatively stationary punches coextensive with the surface of the card and divided into spaced apart rows corresponding to the platen-feed of the card and having a single row of punch-setting pins traveling with the card in typing to progressively align with each row of stationary punches, of mechanical trains of stationary mechanism intermediate the keys and the traveling punch-setting pins to effectively vibrate the punch-setting pins at the position of each row of punches as the typing of the card progresses.

23. In a card-perforating machine having typing keys, the combination with a card-carrying platen movable letter-space distances as typing upon the card progresses, and a series of relatively stationary punches co-extensive with the surface of the card and divided into spaced apart rows corresponding to the platen-feed of the card and having a single row of punch-setting pins traveling with the card in typing to progressively align with each row of stationary punches, of mechanical trains of stationary mechanism intermediate the keys and the traveling punch-setting pins to effectively vibrate the punch-setting pins at the position of each row of punches as the typing of the card progresses, and means operative to restore each train of mechanism independently of the typing keys.

24. In a card-perforating machine having typing keys, the combination with a card-carrying platen movable letter-space distances as typing upon the card progresses, and a series of relatively stationary punches coextensive with the surface of the card and divided into spaced apart rows correspond-

ing to the platen-feed of the card and having a single row of punch-setting pins traveling horizontally with the card in typing to progressively align with each row of stationary punches, of mechanical trains of stationary mechanism intermediate the keys and the traveling punch-setting pins to effectively vibrate the punch-setting pins at the position of each row of punches as the typing of the card progresses, each train of mechanism including a vertically disposed frame vibrated by the keys in typing each character and each frame having a universal bar operative to overlie and depress its punch-setting pin at any row of stationary punches.

25. In a card-perforating machine having typing keys, the combination with a card-carrying platen movable letter-space distances as typing upon the card progresses, and a series of relatively stationary punches coextensive with the surface of the card and divided into spaced apart rows corresponding to the platen-feed of the card and having a single row of punch-setting pins traveling with the card in typing to progressively align with each row of stationary punches, of mechanical trains of stationary mechanism intermediate the keys and the traveling punch-setting pins to effectively vibrate the punch-setting pins at the position of each row of punches as the typing of the card progresses, each train of mechanism including a frame connectible with a traveling punch-setting pin and a rock-shaft to vibrate the frame when rocked by the keys.

26. In a card-perforating and typewriting machine, the combination with a plurality of stationary perforating elements, including a plurality of rows of punches forming a rectangular bank for perforating a card and keys for typing upon the card, of a single row of settable punch-indexing traveling elements mounted above and spaced correspondingly with a row of punches, key-actuated means including a permutating mechanism for setting up said indexing elements singly and in groups, according to a prearranged plan to represent, by perforations in the card, the character typed by each key operation thereon, said key-actuated means including a plurality of stationary parallel punch-selecting bars mounted over the elements and coextensive with the entire length of the punch bank, there being one bar for each element, said permutating mechanism including a series of actuating members for said bars, and a second series of key-actuated members, one for each key mounted perpendicularly to the punch-selecting members and effective to engage therewith, one of said series having a system of formation in certain of its members, whereby motion may be transmitted therefrom to certain of the members in the

other series, effective to set up said indexing elements.

27. In a machine having typing instrumentalities including keys and a card-perforator having a plurality of rows of stationary punches, the combination of a traveling punch-indexing device including a single row of punch-set-up elements and a carriage effective to register the same with any row of punches, mechanism stationary with respect to the travel of the punch-indexing device and mounted over all of the punches, actuatable by the keys to control said indexing device by direct mechanical movement, said indexing device effective to travel between said key-actuable mechanism and the punches, a plurality of interponents between said mechanism and the keys, one for each key, effective to set up said elements in groups, with one movement of the key, according to a predetermined plan to represent, by perforations in the card, the character typed by each operation of said instrumentalities, and means to perforate the card after the indexed elements have been set up.

ALFRED G. F. KUROWSKI.
